UNITED STATES PATENT OFFICE.

ROBERT S. STEPHENSON, OF ALLEGHENY, PENNSYLVANIA, ASSIGNOR
OF ONE-HALF TO JOHN S. GRAHAM, OF SAME PLACE, AND SAMUEL
S. BALDWIN, OF NEW CASTLE, PENNSYLVANIA.

STOVE.

SPECIFICATION forming part of Letters Patent No. 640,427, dated January 2, 1900.

Application filed June 5, 1899. Serial No. 719,384. (No model.)

To all whom it may concern:

Be it known that I, ROBERT S. STEPHENSON, a citizen of the United States, residing at Allegheny, in the county of Allegheny and 5 State of Pennsylvania, have invented a new and useful Improvement in Stoves, of which the following is a specification.

My invention relates to stoves, and has special reference to laundry-stoves for burning gas.

The object of my invention is to provide a cheap and simple form of laundry-stove for the burning of natural gas in an economical and practical manner, as well as one which 15 will provide for a great heating-surface therein.

My invention consists, generally stated, in the novel arrangement, construction, and combination of parts, as hereinafter more specifically set forth and described, and particularly pointed out in the claims.

To enable others skilled in the art to which my invention appertains to construct and use the stove, I will describe the same more fully, 25 referring to the accompanying drawings, in which—

Figure 1 is a top view of a laundry-stove, showing my invention applied thereto; and Fig. 2 is a cross-section thereof.

Like letters herein indicate like parts in each of the figures of the drawings.

My improved laundry-stove is shown at 1 and is provided with the base 2, having the air-spaces 3 therein, and to which are connected the legs 4 for supporting the stove 1. Removably fitting on top of the base 2 is the hollow member 4', which is provided with the side troughs or channels 5, front trough or channel 6, and back trough or channel 7 there- 35

40 in, and removably fitting over the top of the hollow member 4' is the top or cover 8 of the stove 1, which is provided with the side trough or channel 9, front trough or channel 10, and back trough or channel 11 therein, 45 which are opposite to and correspond with the side troughs or channels 5, front trough or channel 6, and back trough or channel 7 in the hollow member 4', and are adapted to form the side flue 12, front flue 13, and rear

flue 14. The top or cover 8 is provided with 50 the openings 15' for the reception of the lids 15 therein and the flange 16' thereon, which extends around an opening 16 for connecting a draft or chimney pipe thereto. Burners 17, having gas-orifices 17' therein, extend horizontally across the interior 1' of the stove 1 and are supported within base portion 2 and hollow member 4' of the stove 1, and air-mixers 18 are connected to the ends of the burners 17 and form part of valves 19, which are 60 connected to a gas-supply pipe 20. Openings 21 are formed in the sides and back of the walls 8' of the top or cover 8 and within the sides and back of the inner walls 4" of the hollow member 4' for the entrance of the products of combustion from the burners 17 to the side flues 12, front flue 13, and rear flue 14, 65 and plates 22 and 23, having air-openings 22' and 23' therein, are supported within the base portion 2 of the stove 1 for the supplying of 70 cold air to the burners 17 to aid combustion.

The operation of my improved laundry-stove is as follows: The parts of the stove 1 being in position and the gas-valves 19 opened to allow the gas to enter the burners 17 75 through the mixers 18 from the supply-pipe 20, the escaping gas can then be ignited at the orifices 17' of the burners 17, and the gas as it issues therefrom and burns will be directed against the top or cover 8 on the objects thereon to heat the same. The products of combustion from the burners will pass through the openings 21 in the walls 4" of the hollow member 4' under the cover 8 into the side flue 12, front flue 13, and rear flue 14 85 and travel around the same to escape through the opening 16 of the cover 8 into the draft or chimney pipe connected thereto.

It will thus be seen that my improved laundry-stove is cheap in its construction and operation and by its use great heating and radiating surface is obtained by the flues used for the passage of the products of combustion, as well as a great saving in the economical use of the gas consumed therein. 90

What I claim as my invention, and desire to secure by Letters Patent, is—

1. In a stove, the combination of gas-burn-

- ers located therein, a box fitting above said gas-burners and provided with flues therein communicating with the draft or escape pipe and a series of openings in the inner walls of 5 said box adjacent to the top thereof adapted to connect the flues with the interior of the stove for the passage of the products of combustion from the interior of the stove to the flues and escape-pipe.
- 10 2. In a stove, the combination of gas-burners located therein, a box fitting above said gas-burners and provided with flues therein communicating with the draft or escape pipe, a top or cover fitting over said box, and a series of openings in the inner walls of said box 15 adjacent to the top or cover adapted to connect the flues with the interior of the stove for the passage of the products of combustion from the interior of the stove to the flues and escape-pipe.
- 15 3. In a stove, the combination of gas-burners located therein, a base portion, a hollow portion on said base portion and provided with troughs or channels therein, a top or 20 cover fitting over said hollow portion and adapted to form flues by said troughs or channels therein for the passage of the products of combustion to the draft or escape pipe, and openings in the sides of said flues connecting the same with the interior of said stove 25 for the entrance of the products of combustion into said flues.
- 30 4. In a stove, the combination of gas-burners located therein, a base portion, a hollow

member fitting over said base portion and provided with a trough or channel therein, a top or cover fitting over said hollow member and provided with a trough or channel therein corresponding to and opposite the trough or channel in the hollow member, said troughs or channels forming flues for the passage of the products of combustion to the draft or escape pipe, and openings connecting said flues with the interior of said stove for the entrance of the products of combustion into said flues. 35

5. In a stove, the combination of gas-burners located therein, a base portion, a hollow member fitting over said base portion and provided with a trough or channel extending around the same, a top or cover fitting over 40 said hollow member and provided with a trough or channel extending around the same corresponding to and opposite the trough or channel in the hollow member, said troughs or channels forming flues for the passage of 45 the products of combustion to the draft or escape pipe, and openings in the inner walls of the hollow member and top or cover for the passage of the products of combustion from the interior of the stove into the flues. 50

In testimony whereof I have hereunto set my hand, at Pittsburg, in the county of Allegheny and State of Pennsylvania, this 24th day of May, A. D. 1899.

ROBERT S. STEPHENSON.
